CONTROLLING SYSTEM FOR SOUND RECORDING DEVICES

Ferguson Hall, Shenandoah, Iowa

Application July 20, 1933, Serial No. 681,388

14 Claims. (Cl. 179—100.4)

This invention is directed to a controlling system for sound recording devices, wherein the sound waves to be recorded are the controlling factor in the starting and stopping of the sound recording device.

The primary object of the invention is the provision of a system, in the use of which any sound recording machine is automatically set in operation by the origin of the sound waves to be recorded on that machine, with the system also providing for the automatic stopping of the recording machine at the cessation of the sound waves. Thus, for example, in the use of a dictaphone for the recording of the human voice, the initial tones will automatically start the machine for recording purposes and the cessation of such tones will automatically stop the machine.

The system, generally speaking, includes a sound recording mechanism, together with a source of electrical pulsations of the same form as those of the recorded sound, with means responsive to said pulsations for maintaining the latter at a constant amplitude, together with means operated by said pulsations for controlling the operation of the recording mechanism. Therefore, the act of recording and the control of the recording mechanism per se is concurrent with the pulsations.

The invention, therefore, is directed to an automatic volume control, which in turn governs a voice controlled relay or other equivalent mechanically or electrically controlling means for the manual operation of the recorder. The volume control maintains the constant level of the audible frequency waves and the operation of the recorder governing relay is dependent upon this fact.

The invention is illustrated in the accompanying drawing, in which:—

Figure 1 is a diagrammatic view of the system in at least a preferred form of the arrangement. Figure 2 is a diagrammatic view of the tube and circuits through which the relay is controlled, as indicated in Figure 1, this figure showing additionally electrical means for retarding the breaking of the relay or plate circuit in order to prevent the de-energization of the recorder operating mechanism control in the intervals in which pulsations are absent from the volume control circuit.

In the system illustrated, 1 indicates a microphone and 2 a conventional audio-amplifier connected with the microphone. The audio-transformers 3 and 4 have their primary windings 5 in connection with the audio-amplifier so that the

current from the amplifier is impressed on the primary windings. The transformer 3 is designed to multiply the voltage applied to its primary windings and to separate the current of the output of the amplifier from the input circuit of the amplifier tube, indicated at 6. This tube will be hereinafter referred to as the controlled tube.

The secondary winding 7 of the transformer 3 is connected to the input or grid filament circuit 8 of the controlled tube 6. In series with this circuit 8 is a battery 9 and a resistor 10. The plate current from the controlled tube 6 is led through a choke coil 11, preferably wound upon an iron core and of very high impedance. The choke coil by reason of current change produces a voltage across the terminals of the coil which is directed through a condenser 12, a battery 13 or other source of direct current of sufficient voltage being utilized for plate power.

The secondary of transformer 4 is connected to the grid filament circuit of what may be termed a controlling rectifier tube 14, having included in the circuit a biasing battery 15. The plate circuit from the tube 14 includes a choke coil 16, the plate power being provided by a source of direct current 17 and the circuit including the resistor 10 heretofore referred to. Condensers 18 and 19 are connected in plate circuit.

For the purposes of governing the starting and stopping of the recording mechanism, there is provided a tube 20, the grid filament circuit 21 of which includes a secondary 22 and audio-transformer 23, the primary 24 of which is in circuit with the recording system per se beyond the condenser 12. The circuit 21 includes a bias battery 25. The plate current from tube 20 including a supply battery 26 flows through the windings of a relay 27. This relay serves to close a circuit 28 having a source of energy 29 and operating to energize an electro-magnet 30 for operating a clutch 31 introduced into a mechanical system for actuating a recorder 32, the recording features of which are in circuit with the system beyond the condenser 12, as shown. Obviously, of course, the circuit 28 may be utilized to directly actuate a prime mover by which the recorder is directly operated as distinguished from the clutch control illustrated. The invention is to be considered up to and including the circuit 28 and this circuit is to be utilized in any conventional or desired manner and with any necessary mechanical or electrical means for operating the actuating mechanism of the recorder or other instrument on which the record is to be made.

With particular regard to the operation, it will

be apparent that the pulsations from the microphone are amplified and impressed in the primary windings of the transformers 3 and 4. The transformer 3 multiplies the voltage for the grid filament circuit of the controlled tube 6. As understood, complete current is governed and controlled in a large measure by the voltage between the grid and filament. Small variations in grid voltage will cause comparatively large variations in the plate current. The more negative the grid is with respect to the filament, the more the plate current is decreased. The bias battery 9 determines a certain definite amount of said current which normally flows when there is no excitation from the transformer 3. Under application of exciting voltage, the value of the plate current varies. These slight pulsations in plate current are exact replicas of the pulsations produced by the microphone and such pass through the choke coil 11. The voltage change in current through the coil is directed through the condenser 12 and operates the recording mechanism in the recorder 32.

The controlling rectifier tube 14 is served from the audio-amplifier. The biasing battery 15 provides a negative bias on the grid and is of such value as to just barely shut off all the current in the plate circuit in the absence of exciting voltage from the transformer 4. Thus in the absence of exciting voltage from the transformer, there is practically no plate current. As the alternating voltage from the transformer 4 is applied to the grid, the grid voltage alternately becomes more negative than the cut-off voltage and alternately less negative than the cut-off voltage. In the periods where the grid is less negative than the cut-off voltage, the current will flow in the plate circuit. During the period when the grid is more negative than the cut-off voltage, no plate current will flow. It follows that the greater the excitation voltage, the greater the amount of current that will flow in the plate circuit. If there is no plate current flowing, there is no voltage drop across resistor 10. Therefore, this resistor has no effect on the controlled tube 6. When plate current is flowing, however, and voltage drop occurs in resistor 10, this voltage is added to the bias produced by battery 9 in the grid filament circuit of the controlled tube. Obviously, the greater the input voltage to transformers 3 and 4, the greater the action of resistor 10 and the greater the decrease in amplification in the controlled tube. By selection of appropriate values for the different components of the circuits, the amplification could be made to decrease linearly with respect to the increase in input voltage, whereby the level of volume would be practically constant.

The choke coil 16 and condensers 18 and 19 iron out the individual pulsations in the plate current of controlling tube 14. This prevents changes in the plate current faster than the natural period of this system. This natural period can be controlled by suitably choosing values, for example by making the inductance of the coil 16 and the capacity of the condensers suitably large.

In connection with the tube 20 which controls the relay or other mechanical power generation for the recorder, it will be apparent that the transformer 23 will serve to excite the grid circuit 21 of the tube 20 immediately following the origin of sound in the microphone 1. The bias battery 25 is here adjusted to approximately cut off the plate current in the absence of excitation. The amount of plate current flowing will, of

course, depend upon the amplitude of the exciting voltage from the transformer 23. The plate current will flow through the windings of relay 27 and so control the auxiliary circuit 28 for directly governing the mechanical operation of the recorder.

Provision must be made, of course, for maintaining the voice controlled relay circuit in the absence of pulsations in the volume control circuit as, for example, between words and incident to short pauses in the sound delivered to the microphone. This may be accomplished in several ways, but in accordance with the provision herein it is preferred that such should be accomplished electrically, and for this purpose and referring more particularly to Figure 2, it is to be noted that there is arranged in the grid circuit 21 of the tube 20 an auxiliary circuit including a rectifier 33, a condenser 34, and a resistance 35. The rectifier is so arranged that its directional effect permits the flowing of positive electricity to the grid side of the condenser 34. The exciting voltage from the transformer 23 will then charge the condenser 34 with a positive voltage on the grid side. This charge cannot leak off owing to the directional effect of the rectifier 33.

Thus, during the period of excitation, the condenser 34 remains charged positively on the grid side and will not interfere with the flow of plate current. When the excitation stops, however, as in the pauses referred to, the accumulated charge on the condenser 34 is utilized to maintain the grid positive through the time lag incident to the character of the resistor 35. There is thus direct provision for maintaining the specific recorder control circuit closed to maintain the recorder in operation during the relatively short intervals necessitated by pauses in the delivery of the sound waves to the microphone. Of course, the character of the resistor and the relation of the parts may be readily selected to determine this time lag to take care of all usual pauses referred to.

I claim:—

1. In a sound recording system, means for utilizing the sound waves of the sound to be recorded for producing electrical pulsations, means for amplifying said electrical pulsations, means controlled by the sound waves for maintaining the volume level of the amplified pulsations substantially constant, a recorder for receiving and recording the amplified constant volume electrical pulsations, means for operating the recorder, and means responsive to the amplified constant volume electrical pulsations for governing said operating means.

2. A sound recording system including means for transposing sound waves into electrical pulsations, means for amplifying said pulsations, means controlled by the sound waves for maintaining the volume level substantially constant, a recorder for receiving and recording the electrical pulsations under amplified constant volume level output, mechanism for operating the recorder, means responsive to the electrical pulsations being recorded to control the operating means for the recorder, and means for utilizing the electrical pulsations being recorded to maintain operative influence on the operating means of the recorder during limited cessation of sound waves.

3. In a sound recording system, means for utilizing the sound waves of the sound to be recorded for producing electrical pulsations, means for amplifying said electrical pulsations, means

- controlled by the sound waves for maintaining the volume level of the amplified pulsations substantially constant, a recorder for receiving and recording the amplified constant volume electrical pulsations, means for operating the recorder, and a vacuum tube controlled relay for governing said operating means.
4. A sound recording system including means for transposing sound waves into electrical pulsations, means for amplifying said pulsations, means controlled by the sound waves for maintaining the volume level substantially constant, a recorder for receiving and recording the electrical pulsations under amplified constant volume level output, mechanism for operating the recorder, a vacuum tube controlled relay to control the operating means for the recorder, and means for utilizing the electrical pulsations being recorded to maintain operative influence on the operating means of the recorder during limited cessation of sound waves.
5. In a sound recording system, a sound recording mechanism, a source of electrical pulsations of the same form as those of the recorded sound, means for amplifying said electrical pulsations, means for controlling the amplification to maintain the same substantially constant for recording purposes on said sound recording mechanism, and means responsive to said constant volume pulsations for directly governing the actuation of the recording mechanism.
6. A system as described in claim 5, wherein said means is in the form of a vacuum tube controlled relay.
7. A system as described in claim 5, wherein said means is in the form of a vacuum tube controlled relay and including means for accumulating a charge during excitation of said vacuum tube controlled relay and releasing this charge for service in maintaining operation of said relay during limited absence of such excitation.
8. In a sound recording system, a recording mechanism, means for utilizing the waves of the sound to be recorded for producing electrical pulsations of identical form, means for amplifying said electrical pulsations, means controlled by the sound waves for maintaining the volume level of the amplified pulsations substantially constant, means for operating the recorder, and means responsive to the amplified constant volume electrical pulsations for governing said operating means.
9. A sound recording system including means for transposing sound waves into electrical pulsations, means for amplifying said pulsations, means controlled by the sound waves for maintaining the volume level substantially constant, a recorder for receiving and recording the electrical pulsations under the amplified constant volume level output, mechanism for operating the recorder, means electrically responsive to the amplified constant volume level electrical pulsations to control the operating mechanism, and additional means responsive to said electrical impulses for maintaining operative influence on the operating means of the recorder during limited cessation of the sound waves, said additional means utilizing said electrical pulsations for creating a charge of electricity and the utilization of said charge to maintain the operative influence on said operating means during cessation of said electrical impulses.
10. A construction as defined in claim 9, wherein said additional means includes a rectifier for the electrical pulsations, a condenser for accumulating direct currents from the rectifier, and a resistor to dissipate the charge over a predetermined period of time.
11. In a sound recording system, means for utilizing the sound waves of the sound to be recorded for producing electrical pulsations, a recorder for receiving and recording said pulsations, an electrical control network including an amplifier tube, an amplification control tube, means for controlling the amplification of said amplifier tube with rectified pulsations from said control tube, a rectifier tube, said rectifier tube being excited and controlled by said pulsations and acting to rectify said amplified pulsations, and means responsive to said rectified pulsations for controlling the motive portions of said recording mechanism.
12. In a sound recording system, means for utilizing the sound waves of the sound to be recorded for producing electrical pulsations, a recorder for receiving and recording said pulsations, an electrical control network including an amplifier tube, an amplification control tube, means for controlling the amplification of said amplifier tube with rectified pulsations from said control tube, a rectifier tube, said rectifier tube being excited and controlled by said pulsations and acting to rectify said amplified pulsations, an associated circuit including resistance and capacity for creating an electrical charge for governing the grid bias voltage of said rectifier tube, and means responsive to said rectified pulsations for controlling the motive portions of said recording mechanism.
13. In a sound recording system, a sound recording mechanism, a source of electrical pulsations of the same form as those of the recorded sound, means for amplifying said electrical pulsations, means for controlling the amplification to maintain the same substantially constant, and a vacuum tube controlled relay including means for accumulating a charge during excitation of said vacuum tube controlled relay and releasing this charge for service in maintaining operation of said relay during limited absence of such excitation.
14. In a sound recording system, the combination of a sound recording mechanism, means for utilizing the waves of the sound to be recorded for producing electrical pulsations of identical form, means for amplifying said electrical pulsations, means controlled by the sound waves for maintaining the volume level of the amplified pulsations substantially constant, means for operating the recorder, and means responsive to the amplified constant volume electrical pulsations for governing said operating means.
